UNITED STATES PATENT OFFICE.

CHARLES A. POWELL AND DAWSON M. HUMISTON, OF PERU, ILLINOIS.

CASH-REGISTER.

SPECIFICATION forming part of Letters Patent No. 537,067, dated April 9, 1895.

Application filed January 27, 1894. Serial No. 498,246. (No model.)

To all whom it may concern:

Be it known that we, CHARLES A. POWELL and DAWSON M. HUMISTON, of Peru, in the county of La Salle and State of Illinois, have 5 invented certain new and useful Improvements in Cash-Registers; and we do hereby declare the following to be a full, clear, and exact description of the invention, such as will enable others skilled in the art to which 10 it appertains to make and use the same.

This invention relates to cash registers and has for its object to provide simple and effective means for registering the amount of sale and keeping tally of the total amount registered by each key.

With these and other objects in view the invention consists of the construction and arrangement of the several parts, as will be more fully hereinafter described and claimed.

20 In the drawings: Figure 1 is a front elevation of the cash register embodying the invention and broken away to show the interior construction. Fig. 2 is a transverse vertical section taken through one of the keys and the 25 adjacent mechanism. Fig. 3 is a plan view of a portion of the registering table. Fig. 4 is a detail view in rear elevation of the drawer locking mechanism.

Similar numerals of reference are employed 30 to indicate corresponding parts in the several views.

Referring to the drawings, the numeral 1 designates an exterior casing in which is mounted a cash drawer or till 2 and having 35 in the upper portion thereof a transparent panel 3 through which the tablets in connection with the several keys and bearing the amount of sale may be made visible. In the back portion of the casing 1 is mounted a series of vertically disposed tubes 4 having upper entrance mouths 5 and lower forwardly grooved ends 6, and adjacent to the said tubes and in connection with each one of the latter are vertically disposed registering bars 7 bearing 40 the aforesaid tablets on their upper ends and adjacent to the said upper ends the registering bars are engaged by operating keys 8 which project from the front of the casing in a horizontal plane and are supplied with 45 indicating finger buttons 9. The rear or inner ends of the keys 8 are supplied with fulcrums 10 which fit into openings in the regis-

tering bars 7 and loosely engage said bars. The lower portions of the bars 7 are provided with openings 11 and below the said openings 55 are shoulders or ratchet teeth 12. The openings 11 are normally in alignment with the lower forwardly bent open ends 6 of the tubes 4 and in front of the said openings 11 when the bars 7 are in their normal position is a 60 guard 13. The tubes 4 are filled with a series of balls 14 which are placed therein through the mouths 5 and are fed from the lower ends of the said tubes into the openings 11, the dimension of the said opening being large 65 enough to receive one ball only at a time.

Adjacent to the upper termination of the rear portion of the guard 13, or secured on the top of the same is the rear end of an inclined registering table 15 having a series of 70 grooves 16 therein intersected or separated by a series of bars 17, the grooves 16 being of the same dimension as the opening 11, in each bar so as to receive the balls 14. The bars 17 are separated or divided into spaces 75 which are numbered from 1 upward in the first column of dollars; from 2 upward in the second column of dollars; from 3 upward in the third column of dollars; from 4 upward in the fourth column of dollars; from 5 upward in the fifth column of dollars; from 10 upward in the sixth column of dollars; and from 20 upward in the seventh column of 80 dollars. The cents column is arranged in a similar manner starting from the right and 85 running toward the center. It will be understood, of course, that the keys 8 have numbers corresponding to the ribs or grooves in the registering table in accordance with the numbers represented at the bottom of each of 90 said ribs.

A central spring actuated key 18 is mounted in the register in a vertical position and has a lower collar or shoulder 19 which is adapted to engage an elbow lever 20 extending entirely across the length of the machine and normally engaging with the uppermost of the shoulders or ratchet teeth 12 in all the bars 7 and when the said key is depressed all the bars 7 that are raised are dropped simultaneously. This key serves the purpose of unlocking the drawer and at the same time releasing any indicator which may be exposed from the previous operation of any one of the 95 100

keys 8, but without operating the registering mechanism. Pivoted to one of the journals of this lever 20 is a depending angular lever 21 which forms a latch for holding the drawer. 5 This normally rests in the position shown in Fig. 2 with its lower arm projecting downwardly and engaging a notched stock 22 at the rear of the till or drawer. The lever 20 has a pin 20^a projecting laterally therefrom which 10 engages the upper arm of said angular lever 21 so that the latter is raised by raising the rear end of said lever 20 but may have upward movement independent of said lever. When 15 one of the keys 8 is actuated to raise its bar 7, the lever 20 is drawn up, carrying with it the angular lever 21 which is drawn out of engagement with the stock 22, permits the drawer or till to be opened and allows the bars 7 previously raised to drop by gravity, 20 being held in elevation by engagement with the inner end of the lever 20, with the lower shoulder or ratchet tooth 12.

When the drawer is opened a ratchet bar 23 mounted thereon strikes a hammer 24 in 25 the path of movement thereof which sounds a gong 25 to give an alarm that the drawer is being opened. When any one of the keys is depressed and the bar 7 raised the ball 14 carried in the opening 11 thereof is brought in 30 line with the proper groove 16 and rolls from the said bar 7 forwardly through the said groove 16. The said bar 7 that has been raised stays in this position until it is lowered in the manner previously set forth and it will 35 be seen that each amount placed in the drawer or till is registered and added. When the casting is opened the sum total of the amount registered by the machine entire can be quickly ascertained. The balls 14 are successively fed into the openings 11 of the bars 7 when the latter have been relieved of the balls carried thereby in their upward movement and when they again reach a lower level. When the drawer or till is closed the stop 22 40 engages the latch 21 and locks the latter against movement until released, as before set forth.

It will be understood that many minor changes in the details, proportion and form 50 of the several parts might be made and substituted for those shown and described without in the least departing from the nature or spirit of the invention.

Having thus described the invention, what 55 is claimed as new is—

1. In a cash register, the combination with the main frame having key levers therein registering different amounts, a series of vertically disposed tubes containing balls, one for 60 each key lever, vertically disposed registering bars, one for each tube and key lever, the said bars provided with openings therein for the reception of one ball at a time and adapted to be raised by the depression of its key lever, 65 the said bars having notches at their lower ends, a till or drawer and locking mechanism therefor engaged by the notches and released

by the upward movement of said bars and an inclined registering table having longitudinal independent grooves upon its upper 70 surface, the said grooves representing respectively amounts corresponding to the number of the key lever, whereby upon the depression of the key lever representing a certain amount, a ball will be elevated from the lower 75 end of the tube corresponding with said lever and deposited upon the registering table in a groove corresponding in amount with said key lever, substantially as and for the purposes specified. 80

2. In a cash register, the combination with a main frame having key levers therein registering different amounts, a series of key bars attached thereto and an elbow lever engaging notches in the lower ends of said bars 85 and adapted to simultaneously drop all of the same that are raised and release the drawer without actuating the registering mechanism and a single key independent of said key levers adapted to actuate said elbow lever, substantially as and for the purposes specified. 90

3. In a cash register, the combination with a main frame having key levers therein registering different amounts and a series of vertically disposed registering bars connected to 95 said levers provided with notches at the lower end thereof, a drawer or till mounted for movement in said frame and locking mechanism therefor consisting of a pivoted angle lever adapted to fit a notch at the rear end 100 of the said till or drawer, an elbow lever engaging the notches in said bars having a laterally disposed pin engaging the upper arms of said angle lever, whereby upon the upward movement of said bar, the said angle lever 105 will be elevated out of engagement with the notches in said drawer and the latter will be released, substantially as and for the purposes specified. 110

4. In a cash register, the combination with the main frame having key levers therein registering different amounts, a series of vertically disposed registering bars connected with 115 said key levers and provided with notches at their lower ends, a drawer or till at the lower 120 part of said frame and locking mechanism therefor consisting of a pivoted angle lever adapted to fit a notch at the rear end of said till or drawer and an elbow lever extending laterally across the frame and adapted to engage the notches in the lower ends of said bars having a laterally disposed pin which 125 engages the said angle lever upon the upward movement of any one of said bars, whereby upon the depression of one of the key levers the registering mechanism is actuated and the drawer released and an independent key lever engaging the outer end of 130 said elbow lever whereby upon the depression of said independent key lever the drawer mechanism will be released without actuating the registering mechanism, substantially as and for the purposes specified. 135

5. In a cash register having a series of reg-

istering balls, the combination of elevating bars for said balls, a registering table with grooves therein to receive the balls, keys for operating the bars, a till or drawer having locking mechanism therefor consisting of a pivoted angle lever adapted to fit a notch at the rear end of the said till or drawer, an elbow lever engaging the notches in said bars having a laterally disposed pin engaging the upper ends of said angle lever and a single key engaging said elbow lever, whereby, upon the depression of said lever, the till

or drawer is released without actuating the registering mechanism, substantially as and for the purposes set forth. ¹⁵

In testimony whereof we have signed this specification in the presence of two subscribing witnesses.
